**COMBINED DIAL AND HANDS FOR A CLOCK
OR SIMILAR ARTICLE**

Sidney Goldstein, Brooklyn, N. Y.

Application October 5, 1955, Serial No. 38,236

Term of patent 14 years

(Cl. D42—1)

Fig. 1 is a front elevational view of a combined dial and hands for a clock or similar article showing my new design, and

Fig. 2 is a side elevational view thereof.

I claim:

The ornamental design for a combined dial and hands for a clock or similar article, as shown.
